UNITED STATES PATENT OFFICE.

FRANK KRAEMER, OF LOS ANGELES, CALIFORNIA, ASSIGNOR TO WILLIAM H. GESTRING.

PILOT CHECK.

Application filed April 18, 1927. Serial No. 184,758.

This invention relates to devices used in connection with water-heaters for controlling the ignition of the heating medium.

One of the objects of this invention is to 5 eliminate any turning-on of the main gas burner in a water-heater if the pilot burner has once been extinguished accidentally or otherwise.

Another object is to include a thermostatic 10 element, operative by the pilot burner for controlling the fuel supply.

Other objects will appear from the following description and appended claims as well as from the accompanying drawing, in 15 which—

Fig. 1 is a front elevation of a pilot burner control, including an electric switch to operate a gas control and including also a thermostat, operative by surrounding water when applied to the water-heater, the water thermostat being broken off to facilitate the illustration.

Fig. 2 is a perspective view of terminals mounted on an insulated block for electrically 25 controlling the gas supply through the device illustrated in Fig. 1.

Fig. 3 is a fragmentary side elevation of the electric switch lever.

Fig. 4 is a fragmentary top plan view of the 30 insulated terminals of Fig. 2 and the switch lever of Fig. 3.

As illustrated in Fig. 1, the main gas connection is indicated at 5, below the instrument case 6. This main gas connection is controlled by a valve 7 inserted in the connection, 35 operative by a solenoid 8 in the instrument box 6. This solenoid 8 is inserted into any suitable electric circuit in series with contact terminals 9 and 10. These contact terminals 40 are normally spaced so that the electric circuit is thereby interrupted. For closing the circuit a switch lever 11 is pivotally mounted at 12.

The switch lever 11 is normally held in in- 45 operative position by the thermostat 13. The thermostat 13 is normally inserted into the inside of a water-heater, so as to become influenced by the temperature of the water in the heater. When the water in a heater has 50 reached a desired temperature the thermostat 13 is in expanded position with its controlling end 14 in its uppermost position pressing by its adjusting screw 15 against the lever end 16. The lever end 17 is thereby forced in the direc- 55 tion of the arrow 18, in which manner the connecting rod 19 is caused to force the switch

lever 11 into the inoperative position in which this lever is illustrated.

The pilot burner tube 20 receives its gas supply from the main connection 5, having its 60 fine discharging aperture 21 disposed to discharge the gas against the thermostatic bar 22. When this discharging gas is ignited it naturally heats and thereby expands the thermostatic bar 22 so as to bring the control end 23 65 to its lowermost position, so that the set screw 24 frees the lever end 25. When the lever end 25 is released in this manner, the lever end 26 is free to move in the direction of the arrow 27 to the extent of the slot 28 as long as the 70 lever end 17 with the connecting rod 19 forces the switch lever 11 in the direction of the arrow 18.

Whenever the temperature of the water in the heater decreases so as to lower the control 75 end 14 of the thermostat 13, the lever end 17 is free to move in a direction opposite to the arrow 18, in which direction this lever end and the connecting rod 19 are forced when so freed by the spring 29, thereby bringing the 80 contact switch against the contact terminals 9 and 10, bridging the gap between these terminals 9 and 10. At this moment current may pass through the contact terminals from the lead 30 and through the lead 31 and fur- 85 ther through the solenoid 8 to the lead 32, through which the solenoid affects the valve 7 in the main gas connection 5 to supply a full force of gas to the water-heater.

The water-heater is not shown in the drawing, but it will easily be understood from the above that gas can be supplied through solenoid actions in the manner described.

The switch lever 11 is provided with equalizing means in form of a yielding cross bar 95 33 by which the contact members 34 are equally pressed against the terminals 9 and 10 in the manner illustrated in Fig. 4.

Whenever the pilot burner is extinguished accidentally or otherwise, the thermostat bar 22 contracts to bring the control end 23 to its uppermost position, whereby the lever end 25 is held in its uppermost position so as to hold the lever end 26 pressed in a direction opposite to the arrow 27, whereby the switch lever 11 is held in inoperative position. When so held in inoperative position the thermostat 13 is unable to effect a closing of the switch, even if the water in the heater gets cold, since a mere releasing of the lever end 16 and thereby of the lever end 17 will not allow the switch lever 11 to move into contact making

position against the contracted thermostat bar 22.

It is therefore made impossible to open the fuel supply of a water-heater whenever 5 and as long as the pilot burner is extinguished. Explosions and similar accidents with water-heaters are therefore made impossible when controlled by a pilot check as described here-with.

10 After the pilot burner has been extinguished it can easily be ignited again near the small aperture 21, and as soon as ignited it will heat the thermostat bar 22 and the whole instrument will work in a normal manner again as soon as the thermostat bar 22 is 15 heated to the extent to allow the switch lever 11 to close.

The discharging of gas from the small aperture or jet 21 in the pilot burner pipe 20 as well as the thermostat bar 22 is indicated 20 at 35 in Fig. 1.

Having thus described my invention, I claim:

1. In a pilot check of the class described, 25 in combination with an electric switch for controlling a main gas supply of a water-heater, a thermostat in operative connection with said switch and adapted to be operative by temperature changes in the heater, and a 30 pilot burner embodying an independent sec-

ond thermostat and having its pilot orifice disposed so as to heat said second thermostat, the pilot thermostat being also in operative connection with said switch and adapted to hold the switch inoperative regardless of movements of the first-named thermostat. 35

2. In a pilot check of the class described, a solenoid controlled fuel supply, a thermostat adapted to extend into a water-heater to be influenced by the temperature of the water 40 in the water-heater, an electric circuit in operative connection with said solenoid including normally spaced terminals, a spring-controlled switch, a lever mechanism in operative connection with said switch and with said thermostat by which said switch is held inoperative when the thermostat is expanded, a pilot burner, a thermostat element disposed to be expanded by the heat originating from the pilot burner, and a second lever mechanism in operative connection with said element and the first-named lever mechanism disposed to check the movements of the first-named lever mechanism when the pilot burner is not burning and the cooperating thermostat element is not expanded by the pilot burner. 45 50 55

In testimony that I claim the foregoing as my invention I have signed my name.

FRANK KRAEMER.
